UNITED STATES PATENT OFFICE.

JUDSON A. DE CEW, OF MONTREAL, QUEBEC, CANADA.

BARKING-MACHINE.

1,233,321.

Specification of Letters Patent. Patented July 17, 1917.

Application filed May 5, 1916. Serial No. 95,621.

To all whom it may concern:

Be it known that I, JUDSON A. DE CEW, a subject of the King of Great Britain, and resident of the city of Montreal, in the Province of Quebec and Dominion of Canada, have invented certain new and useful Improvements in Barking-Machines, of which the following is a full, clear, and exact description.

10 This invention relates to improvements in barking machines, and the object is to provide an apparatus for removing bark from logs intended for use as pulp wood, working as nearly as possible automatically and arranged for discharge of the bark with a minimum of trouble.

The device consists essentially of one or more floats or rafts having thereon a suitable framework supporting a revolving drum 20 and a loading apparatus.

In the drawings which illustrate the invention:—

Figure 1 is a plan view of the device.

Fig. 2 is a side elevation.

25 Fig. 3 is a front elevation.

Fig. 4 is a partial longitudinal section of the drum showing the drive.

Fig. 5 is a half combined end elevation and cross section showing the bark cutters.

30 Fig. 6 is an end elevation of the bark slitters on an enlarged scale.

Fig. 7 is a side elevation of the slitting device.

Fig. 8 is a partial view of a modification.

35 Referring more particularly to the drawings, 11 designates a float or floats arranged with an opening 12, which is straddled by a suitable framework 13, containing a revolvable drum or cage 14, arranged on a slight

40 incline, as shown in Fig. 2. A source of power 15 is mounted at a suitable point on the framework, and is suitably geared to a shaft 16, which drives the drum by means of a plurality of toothed sprocket chains 17.

45 At the end of the framework adjacent the elevated end of the drum, a boom 18 is provided, from the end of which an elevator frame 19 is suitably suspended, having a constantly moving toothed chain 20, driven

50 by suitable gearing from the shaft 16. The lower end of this elevator is submerged in

the manner well known in connection with saw mills, so that logs may be floated to the lower end of the elevator and will be carried up thereby and discharged into the drum. 55

The drum consists of a plurality of longitudinal parallel bars 21 of any suitable section, but preferably square, secured in position by a suitable number of rings 22. These rings, in addition to holding the bars 60

in position, form tracks upon which the drum rotates, and by which it is supported upon rollers 23 in the well known manner. The bars may be fixed or revolvable in the rings as desired. The teeth of the drive 65

chains 17 may engage between the bars, which will act as gear teeth, but preferably engage a sprocket ring 22^a fixed to one of the rings 22, as clearly shown in Fig. 4. A suitable number of additional rings 24 70

are provided which project a suitable distance within the bars and are sharpened to a suitable cutting edge 25. Intermediate these rings 24, additional rings 26 are provided having teeth 27 adapted to engage the bark of a log. The drum is held together by longitudinal bolts 28 outside the bars, passing through the rings 22, 24 and 26 and holding them in place by means of fillers 29 and diagonal braces 30. At the top 80

of the elevator, cutting knives 31 of any suitable type are provided. These knives are preferably of the double bladed rotary type, shown in Figs. 6 and 7, and are mounted in the sides of the elevator in such position that they will engage and slit the bark of either large or small logs, as clearly shown in Fig. 6. Mounted above the knives 85

32 is an additional slitting knife carried on a weighted lever 33, the free extremity 90 of which extends downwardly a suitable distance and then slopes gradually upward. The operation of the device is substantially as follows:—As a log is brought up the elevator, the bark is longitudinally cut, torn 95 or perforated to a certain extent by the toothed elevator chain. In addition, the log is forced between the cutters 31, which cut the bark longitudinally. Upon being discharged into the revolving drum, the log is 100 carried partially around by the drum, owing to the toothed rings 26, but at a certain

point, falls back and rolls to the lowest portion of the drum. During this rolling, the bark is circumferentially cut by the sharp edges 25 of the rings 24, and is also more or less torn in a circumferential direction by the toothed rings 26, so that the bark is longitudinally and circumferentially scored. As the drum revolves continuously, the log repeats this operation, and is in addition 10 continually battered against the comparatively sharp edges of the bars 21, which operate to knock, peel or grind off the bark, the smaller fragments of which at once fall through the float opening 12 into the water, 15 and are carried away, while the larger fragments are broken up and later fall from the drum into the water, and are also carried away. Owing to the slight inclination of the drum, the logs work gradually toward 20 the lower end, from which they are discharged thoroughly freed of bark. The cutters 31 previously mentioned in this paragraph are so positioned that with the cutter 32 they will slit the bark of any ordinary sized log at approximately equal distances apart. Small logs will engage the lower blade of each cutter, while large logs will engage the upper blade, as clearly shown in Fig. 6. After a log has passed, the 25 floating knife 32 drops. The next log coming up the chute passes under the inclined end of the arm 33, and thus raises the knife, so that the same does not catch on the end of the log.

30 The device is simple, inexpensive and efficient.

In districts where it is not permissible to discharge bark into the rivers, suitable scows may be floated into the opening 12 and re- 40 moved when full.

Having thus described my invention, what I claim is:—

1. A barking machine, comprising a pair of spaced floats, a frame connecting said 45 floats, a revoluble barking drum mounted in the frame above the space between the floats whereby refuse falls direct from the drum into the water, and an elevator arranged to convey logs from the water and discharge 50 same into the drum.

2. A barking machine, comprising a revolving drum, circumferential knives therein, circumferential log carrying means in the drum, a log feeding device, and longitudinal bark cutting means in said feeding 55 device.

3. In a barking machine, a revolving drum, a toothed member in said drum arranged to increase and accelerate rolling of 60 logs in the drum, and a knife in the drum disposed to cut the bark of logs circumferentially during rolling thereof.

4. In a barking machine, a revolving

drum, a toothed member in said drum arranged to increase and accelerate rolling of 65 logs in the drum, a knife in the drum disposed to cut the bark of logs circumferentially during rolling thereof, a log feeding device for said drum, and means carried by 70 said feeding device arranged to cut the bark of logs longitudinally prior to delivery into the drum.

5. In a barking machine, a drum built up of a plurality of parallel bars, and supporting rings therefor, and toothed drive chains 75 for said drum having the teeth thereof engaging between the bars of the drum.

6. In a barking machine, a longitudinally barred drum, toothed drive chains for said drum, the bars of the drum being arranged 80 to form sprocket teeth for the engagement of the drive chains.

7. In a barking machine, a revoluble drum comprising a plurality of longitudinal bars, a plurality of supporting rings for said bars forming drum supporting tracks, a ring carried by said bars presenting a cutting edge 85 on the inner surface of the drum, and a ring carried by said bars presenting a toothed edge on the inner surface of the drum. 90

8. In a barking machine, a drum comprising a plurality of longitudinal parallel bars polygonal in cross section, rings revolvably supporting said bars and forming drum supporting tracks, a ring carried by said bars 95 having a toothed log transporting edge presented on the inner surface of the drum, a ring carried by the bars having a bark cutting edge presented on the inner surface of the drum, rollers engaging the track rings 100 of said drum, drum revolving means, and means for longitudinally cutting the bark of logs prior to delivery into the drum.

9. In a barking machine, a float, a framework thereon, a barking drum mounted on 105 an incline in said framework comprising a plurality of longitudinal bars, a plurality of rings supporting said bars, rollers mounted in the framework above and below the drum engaging said rings for the support 110 of the drum, a source of power mounted on the framework, a shaft driven thereby, a plurality of toothed drive chains operated by said shaft, having the teeth thereof engaging between the bars of the drum, log 115 transporting means mounted in the drum, means for feeding logs to the drum, and means for longitudinally and circumferentially cutting the bark of logs.

10. In a barking machine, a tumbling 120 drum, means for feeding logs into the drum, and bark slitting means positioned in the path of logs entering the drum and arranged to slit bark longitudinally by reason of log movement, said slitting means being arranged to variably engage and slit the bark 125.

of different sized logs in more than two lines approximately equidistant around the log's circumference.

11. In a barking machine, a barking drum, means for feeding logs thereinto, a plurality of double blade cutters angularly disposed in the path of the logs, and additional cutters flexibly mounted in the path of the log, said cutters being so disposed and the

blades thereof so spaced that the bark of both small and large logs will be slit approximately at uniform distances apart.

In witness whereof, I have hereunto set my hand, in presence of two witnesses,

JUDSON A. DE CEW.
